UNITED STATES PATENT OFFICE.

ROBERT B. HADEN, OF CINCINNATI, OHIO.

INSULATOR.

1,102,656.

Specification of Letters Patent.

Patented July 7, 1914.

Application filed December 15, 1913. Serial No. 806,896.

To all whom it may concern:

Be it known that I, ROBERT B. HADEN, a citizen of the United States, residing at Cincinnati, in the county of Hamilton and State of Ohio, have invented certain new and useful Improvements in Insulators, of which the following is a specification, reference being had to the accompanying drawings:

This invention relates to new and useful improvements in insulators and more particularly to insulators for supporting electric light wires or inclosing the tubes therefor. It is extremely dangerous in handling electric light wires or inclosing tubes therefor which are to be supported at intervals from a wall or posts, and it will be apparent that convenient means should be provided for readily removing or substituting the wires or other things to be supported. However, the usual insulator supports or hangers which are commonly used make no provision for this but require considerable manipulating in order to permit the supporting wire to be removed or to permit another to be inserted.

It is the principal object of my invention therefore, to provide a simple and durable hanger or support for this purpose which shall be capable of quick adjustment to clamp one or more wires or to permit their removal therefrom.

Another object of the present invention is the provision of an insulator and support which will possess advantages in points of efficiency and durability, is inexpensive to manufacture and at the same time is simple in construction and operation.

With the above and other objects in view, the invention consists in the novel features of construction and the combination and arrangement of parts to be hereinafter more fully described, pointed out in the claims and shown in the accompanying drawings, in which—

Figure 1 is a side elevation of an insulator and supporting pin; Fig. 2 is a top plan view, the cover being removed; Fig. 3 is a side elevation of the supporting pin; Fig. 4 is an edge elevation of the same; Fig. 5 is an end elevation of the insulator, the cover thereof being removed; Fig. 6 is a vertical sectional view of the insulator; Fig. 7 is a plan view of the connecting plate, and Fig. 8 is a bottom plan view of the insulator.

Referring more particularly to the drawings, 1 indicates a portion of a cross arm or

support through which the supporting pin 2 is disposed and is securely held in position by means of a nut 3 which is removably engaged upon the lower end thereof. The upper end of the pin 2 is provided with a web member 4 having formed at its upper and lower edge thereof, the outwardly projecting flanges 5 and 6. The web 4 is further reinforced by means of the vertical rods 7 which extend upwardly upon opposite sides thereof. Extending vertically from the upper flange 5 at each end thereof are the posts 8 upon which the body of the insulator is mounted.

The body of the insulator comprises two sections 9 and 10, each section being provided upon the bottom face thereof with an arcuate groove 11 and being further provided with a recess 12 which when the two sections are secured together form an elongated recess adapted to receive the upper end of the web 4 and the flange 5. The sections 9 and 10 of the body of the insulator are provided with vertical openings 13 which are adapted to receive the posts 8 so as to securely hold the same against lateral movement. The section 10 is provided upon its inner end with an inwardly projecting tongue 14 which is cut away at its upper surface to form the shoulder 15 against which the overhanging flange 16 is adapted to abut when the two sections are placed together.

In the practical use of the invention, the sections 9 and 10 are first mounted upon the posts 8, said sections being provided upon their inner faces with semicircular recesses 17, which, when the sections are in position are adapted to form a substantially circular opening therethrough for the reception of the wires or other material to be supported. After the sections have been mounted on the posts 8, the connecting plate 18 is arranged within the recess 19 formed in the upper end of the insulator and is provided at each end thereof with suitable openings 20 which are adapted to receive the upper reduced ends of the posts 8 and nuts 21 are threaded upon the reduced portions of the posts to securely retain the plate in position and hold the sections of the insulators upon the posts. The sections 9 and 10 are spaced somewhat at their upper ends and are provided upon their inner edges with suitable shoulders 22 upon which are adapted to rest outwardly projecting shoulders formed ad-

5 jacent the lower end of the removable block 23. This block is provided in its under surface with an arcuate groove 24 which is adapted to coöperate with the arcuate portions formed in the sections 9 and 10 so as to securely retain a conducting or supply wire within the opening formed by said arcuate portions.

10 In order to exclude the rain and snow from the recess 19, I provide a suitable cover 25 having a downwardly extending flange 26 formed upon its outer edge and adapted to engage over the upper ends of the sections 9 and 10. This cover is preferably 15 formed of the same material, as the insulator and is provided upon its under side with spaced openings 27 which are adapted to receive the nuts 21 and the upper ends of the posts 8. The cover 25 is provided with a recess 26 having inwardly projecting side walls thereof which are adapted to coöperate with the spring member 28 so as to retain the cover in its closed position. The 20 spring member 28 comprises a U-shaped flat 25 spring having its medial portion secured to the plate 18 and its ends curved in opposite directions so as to readily conform to the shape of the opening 28, thus eliminating the accidental removal of the cover.

30 From the above description taken in connection with the accompanying drawings, it will be readily apparent that I have provided a simple and durable insulator and support therefor, whereby conducting or 35 electrical light wires may be quickly and readily arranged in position or removed therefrom. My improved pin which supports the insulator is much stronger than the pins now in use due to the construction of 40 the web 4 and the bracing parts thereof. The insulator itself can be readily constructed of glass or any other desirable material and placed upon the market at a very small cost. It will be noted that in placing the 45 wire within the opening formed by the concave portions, the cover 25 is first removed by moving the same upwardly, the nuts 21 are then removed from the upper ends of the posts 8 and the insulator sections may be 50 quickly and readily withdrawn from the posts.

While I have shown and described the preferred form of my invention, it will be obvious that various changes in the details 55 of construction and in the proportions may be resorted to for successfully carrying my invention into practice without sacrificing any of the novel features or departing from the scope of the appended claims.

What I claim is:

1. A device of the class described includ-

ing a supporting pin, a web member formed integral therewith, flanges formed at the upper and lower ends of said web member, spaced posts mounted upon the upper end of said web member and removable insulator sections mounted upon said posts, as and for the purpose specified. 5

2. A device of the class described including a supporting pin, a web member formed integral with one end thereof, flanges formed upon the upper and lower ends of said web member, spaced posts mounted upon the upper end of said web member, removable insulator sections mounted upon 75 said posts and having recesses to receive the upper flange of the web, and a removable cover mounted upon the top of said insulator sections, as and for the purpose set forth. 80

3. A device of the class described including a supporting pin, a web formed integral therewith, outwardly projecting flanges formed on said web, a sectional insulator removably mounted upon the upper end of said web, said sections being provided with 85 arcuate recesses to form a circular opening, a cover mounted upon said insulator sections and means for removably securing the cover in position. 90

4. A device of the class described including a supporting pin, a web formed integral therewith, insulator sections having recesses to receive the upper end of said web, posts mounted upon said web upon which the insulator sections are removably mounted, a plate connecting the upper ends of said posts and nuts threaded upon the upper ends of said posts to retain the sections in position, a cover removably engaged over the upper ends of said insulator sections having 100 a socket member and a spring member carried by said plate and adapted to be removably engaged within said socket to retain the cover in position. 95

5. A device of the class described including a sectional insulator having a recess in the upper end of each of the sections and an opening between said sections, shoulders formed upon said sections within said opening and a removable block arranged within 110 said opening and having shoulders adapted to engage the shoulders on said sections to support the block and said insulator being provided with a transverse opening, as and for the purpose specified. 105

In testimony whereof I hereunto affix my signature in the presence of two witnesses,

ROBERT B. HADEN.
